UNITED STATES PATENT OFFICE

ABRAHAM COUWENHOVEN, OF BADEN, SWITZERLAND, ASSIGNOR TO AKTIENGESELLSCHAFT BROWN, BOVERI AND CIE, OF BADEN, SWITZERLAND

SCISSORS SHAPE COLLECTOR FOR ELECTRIC VEHICLES

Application filed May 14, 1928, Serial No. 277,721, and in Germany May 18, 1927.

Scissors-shape collectors for electric vehicles have hitherto been so constructed that the upper arms are connected to rigid frames by transverse members and diagonals rigidly fixed to the said arms, whereby a statically multiple determined structure is formed. Such collectors have the disadvantage, owing to the rigid connection of the upper scissors arms, that, on slight inaccuracies occurring in the erection or any twisting of the collector frame due to external influences, serious binding may be produced in the joints of the scissors. The frictional forces thus produced detrimentally affect the functioning of the collector to which must be added the further disadvantage of an increase in the weight of the moving parts due to the reinforcing members themselves. For overcoming these disadvantages it has already been proposed to connect the upper scissors arms of only one half of the collector by transverse struts and diagonals to form a rigid frame, but to use the arms of the other half of the collector as simple compression members. Although this arrangement reduces the liability of binding in the joints, it does not completely remove this difficulty.

By the present invention a scissors-shape collector is produced in which binding in the joints is entirely avoided. According to the invention this is effected by the transverse reinforcement of the scissors being constituted without rigid connections by means of diagonals pivotally connected to the upper scissors arms. Between the upper scissors arms of each half of the collector a single diagonal is provided, which is pivotally connected to the said arms, whereby a statically simple determined structure is created and the scissors can be twisted without causing binding friction in the joints.

A constructional example of the invention is illustrated in the accompanying drawings, Fig. 1 being a perspective view and Fig. 2 a plan view.

Fig. 3 shows a perspective view of a typical joint partly in section between the scissors member and a diagonal;

Fig. 4 shows a similar view of a typical

joint between the scissors members themselves;

Fig. 5 is a perspective view partly in section of a typical joint between a scissors member and a diagonal;

Fig. 6 is a similar view to that of Fig. 5 of another type of joint for the same purpose; and

Fig. 7 is a similar view to that shown in Fig. 5 of another type of joint and for the same purpose.

The underframe arms of the two scissors *a* and *b* of the collector are journalled in the usual manner on the vehicle and are acted on by erecting springs. *e* is the bow mounted on the upper joints of the scissors, which bow is kept in the vertical position by means of separate springs. The upper scissors arms *a₁*, *b₁* of one half of the collector are connected to one another by the diagonal *c* and the arms *a₂*, *b₂* of the other half of the collector by the diagonal *d*. The diagonals *c* and *d* are pivotally connected to the scissors arms.

The scissors of the present device are not rigid, the separate scissors, and the various arms of same being capable of moving independently of one another, while the relative distance of each pair of scissors and their transverse reinforcement is maintained. When during erection a collector of this kind is not mounted perfectly horizontal, it will still be able to rise and fall without any binding friction in the joints, as each pair of scissors arms are capable of moving independently of one another, the diagonals adjusting themselves at any inclination necessary in their pivotal connections. The vertical mobility of the two pairs of scissors, or the scissors arms with respect to one another is limited by the play of the diagonals at the pivotal connections. The current collector, and each pair of scissors are capable of yielding vertically, when the overhead wire does not lie exactly over the middle of the bow, for instance in curves, when the two scissors are unequally loaded. In order to avoid all binding at the pivotal connections of the diagonals it is preferable to make the pivot holes of the latter barrelled, so that they have the mobility of a ball bearing on

the pivots and can adjust themselves readily as illustrated in Figs. 3, 5 and 6 of the drawings. The pivots f may be mounted on shackles g or sleeves which are fixed rigidly so as to be rotatable on the scissors arms f_2 . The joints between the diagonals and the scissors arms may also have the form of universal joints as in Fig. 7 of the drawings. In this case the diagonal member d is pivoted 10 at h to a rotatable member j , which in turn is pivoted by means of the pintle k in the shackle l . The shackle l is in turn mounted on scissor member b_2 . The other joints of the scissor will also suitably be given a ball joint 15 movement on the pivots, by making the pivot holes barrelled as illustrated in Fig. 4 of the drawings, or they may be made of the type shown in Fig. 3 of the drawings.

What I claim is:

20. A scissors shape collector for electric vehicles with transverse reinforcement consisting of diagonal members, wherein the diagonal members are articulated to the upper scissors arms, the upper scissors arms of each 25 half of the collector are connected by a single diagonal member and the pivotal points of the diagonal members are so formed that the scissors of one collector and its arms are capable of being twisted without causing binding friction in the joints, said diagonal members having a ball joint movement on the pivots.

In testimony whereof I have signed my name to this specification.
